INVENTOR

John D. Caruso
BY
Charles H. Keeler
his ATTORNEY

UNITED STATES PATENT OFFICE.

JOHN D. CARUSO, OF NEW YORK, N. Y., ASSIGNOR OF ONE-HALF TO M. CHARLES SCHWEINERT, OF NEW YORK, N. Y.

HAIR CUTTER.

Application filed November 8, 1924. Serial No. 748,520.

My invention relates to improvements in means for cutting hair, and the same has for its object more particularly to provide a simple, efficient and reliable device which 5 may be readily and conveniently used to cut or trim hair.

Further, said invention has for its object to provide a device of the character specified which is drawn through the hair 10 like a comb in performing the cutting operation.

Further, said invention has for its object to provide a device of the character specified in which either side thereof may be disposed with safety in operative position next 15 to the hair to conveniently cut or trim the same.

Further, said invention has for its object to provide a device of the character specified 20 in which the blade extends through and across the toothed portion of the device to permit of the disposition of either side of the device in operative position, and to prevent the device from cutting the user when 25 the device is disposed in either of the operative positions thereof.

Further, said invention has for its object to provide a device of the character specified which may be employed to cut or trim 30 either fine or coarse hair, irrespective of the length thereof.

Other objects will in part be obvious and in part be pointed out hereinafter.

To the attainment of the aforesaid objects 35 and ends my invention consists in the novel details of construction, and in the combination, connection and arrangement of parts hereinafter more fully described and then pointed out in the claims.

40 In the accompanying drawing showing an illustrative embodiment of the invention,

Figure 1 is an elevation, with parts broken away, showing one form of device constructed according to and embodying my said invention;

Figure 2 is an enlarged sectional view thereof on the line 2—2 of Fig. 1;

Figure 3 is an enlarged sectional view thereof on the line 3—3 of Fig. 1; and

50 Figure 4 is an elevation showing a modified form of the device.

Referring to the drawings, the hair cut-

ting or trimming device includes a hair engaging or combing member 10 of suitable length, having a base or shank portion 11 and suitable teeth 12 and 13 extending from said shank. Preferably, the teeth 12 are coarse and widely spaced to permit of the same efficiently engaging coarse or thick hair. The teeth 13 are relatively fine and closely 60 spaced to permit of the efficient engagement of said teeth 13 with relatively fine or thin hair. Figs. 2 and 3 indicate the relative widths of the teeth 12 and 13 in planes transversely of the device. 65

The member 10 has a longitudinal recess or slot 14 therein which extends from the top edge of and through the shank 11 into the inner portions of the teeth 12, 13. The recess 14 also extends longitudinally of the 70 member 10 from end to end thereof to permit of the insertion of the blade 15 endwise into the slot 14 through one of the open ends 14^a thereof. The open ended slot 14 in the member 10 extending from end to end of 75 said member divides the same into opposing yieldable or resilient portions 11^b, adapted to be stressed to firmly grip or clamp the blade 15 therebetween, said blade being coextensive in length with said member 10. 80

The blade 15 is preferably inserted endwise into an end 14^a of said slot 14 and forced inwardly. This method of inserting the blade 15 prevents injury to the cutting edge 16 thereof disposed between the shank 85 11 and the outer ends of the teeth 12, 13.

The blade 15 extending through and across the teeth 12, 13 is protected by the portions of said teeth 12, 13 at opposite sides of the blade 15, which form guards to prevent the user from being cut or injured when the device is used with one side or the other in operative position to cut or trim the hair. 90

The side portions 11^b of the member 10 are 95 maintained in engagement with blade 15 to clamp the same in position by the securing member 17, which is coextensive in length with the member 10. The member 17 has a longitudinal recess or slot 18 therein closed at one end 20 and open at the opposite end 20^a, adapted to receive the shank 11 which may be inserted endwise into the recess 18 through the open end 20^a. The member 17

and the shank 11 have interfitting portions 19 to prevent the member 10 from being pulled out of the recess 18 through the longitudinally open portion thereof. When 5 the member 10 is in position, one end thereof is engaged by the end 20 of the member 17 and the opposite end of the member 10 is engaged by a detent 21 to prevent the member 10 from being accidentally pulled out end- 10 wise. The opposite walls 17^b of the member 17 are resilient so that when the member 10 is disposed therebetween, said side walls 17^b compress the portions 11^b to maintain the same in gripping relation with the blade 15. 15 The member 17 also provides a convenient portion adapted to be grasped by either hand in the use of the device.

As shown in Figs. 1 and 4, the cutting edge 16, 16^a is preferably arranged so that 20 the distance between the same and the outer ends of the teeth 12, 13 or 12^a, 13^a, varies along the device to permit of the use thereof for cutting or trimming either long or short hair, or either thick or fine hair. Preferably 25 the said cutting edge 16, 16^a and the line along which the outer ends of said teeth lie form an acute angle, or converge towards each other, from the end of the device having the coarse teeth 12, 12^a, to the end of the 30 device having the fine teeth 13, 13^a. In Fig. 1 this convergence is obtained by providing teeth 12, 13 which are progressively shorter towards the end of the device having the fine teeth 13, the blade 15 being of uniform 35 width throughout. In Fig. 4 the convergence is obtained by providing teeth 12^a, 13^a of uniform length, the blade 15^a being progressively wider towards the end of the device having the fine teeth 13^a. The member 10^a with its shank 11^a and the member 17^a are in other respects like the corresponding parts illustrated in Figs. 1 to 3.

To use the device, the same is drawn 45 downwardly through the hair like a comb to cut or trim the rough and jagged hair to render the same even and smooth. Owing to the disposition of the blade 15, 15^a within the teeth 12, 13, or 12^a, 13^a, the device can be employed to trim different portions of the 50 hair, using one hand or the other, depending on the position of the portion it is desired to trim. The arm and hand used can be held at a comfortable, convenient angle throughout the operation. Either side of 55 the device may be disposed in operative position next to the hair without the danger of cutting or injuring the user.

For cutting or trimming long or thick hair, the portion 12, 12^a of the device may be 60 employed. For cutting or trimming relatively short or thin hair, the portions 13, 13^a of the device may be employed.

My said invention provides a device which 65 permits of a person cutting or trimming his or her own hair without engaging the serv-

ices of a barber, and the same is of use to women especially for keeping bobbed hair in presentable condition.

Having thus described my said invention, what I claim and desire to secure by Letters Patent is:

1. A device of the character described comprising a member including a shank with teeth projecting therefrom, and a recess within said member adapted to receive 73 a blade, a clamping member having a longitudinally extending recess therein, and serving to receive said shank to retain said blade in position within said first named recess, and means serving to lock said 80 clamping member in position on said shank.

2. A device of the character described comprising a member including a shank with teeth projecting therefrom, and a recess within said member adapted to receive a 85 blade, a clamping member having a longitudinally extending slot therein serving to receive said shank to retain said blade in position; the opposing portions of the surfaces of said members engaging each other 90 throughout the extent thereof, and means serving to retain said members in engaged position.

3. A device of the character described comprising a member including a shank with 95 teeth projecting therefrom, and a recess extending through said shank into said teeth, and adapted to receive a blade, and a clamping member having a longitudinally extending slot therein serving to receive said shank 100 to retain said blade in position, and slidably longitudinally of said shank to and from position thereon; said members having interengaging portions serving to prevent transverse movement thereof relative to each 105 other.

4. A device of the character described comprising a member including a shank with teeth projecting therefrom, and a recess extending through said shank into said teeth, and adapted to receive a blade, a clamping member having a longitudinally extending slot therein serving to receive said shank to retain said blade in position, and slidably longitudinally of said shank to and from 110 position thereon, and means for locking said members together against longitudinal movement relative to each other.

5. A device of the character described comprising a member including a shank with teeth projecting therefrom, and a recess extending through said shank into said teeth, a blade having a length substantially coextensive with that of said toothed portion, and disposed in said recess, a clamping member having a longitudinally extending slot therein serving to receive said shank with the opposing portions of said members engaging each other throughout the extent thereof, and slidably longitudinally 125 130

- of said shank to and from position thereon, means for locking said members together against longitudinal movement, and inter-engaging means on said members serving to hold the same together against transverse movement.
6. A device of the character described comprising an elongated shank, coarse teeth extending therefrom along a portion thereof, relatively fine teeth extending therefrom along the remaining portion thereof; said shank and the inner portions of said teeth having a recess therein extending through said shank into said teeth, a blade having a length substantially coextensive with said teeth, and disposed in said recess, a cutting edge on said blade arranged between the inner and outer ends of said teeth; said cutting edge and the line along which the outer ends of said teeth lie converging towards each other from the end of the device having the coarse teeth to the end having the fine teeth, and a slotted member receiving said shank to compress the opposite sides thereof into clamping relation with said blade.
7. A device of the character described comprising a member including a shank with teeth projecting therefrom, and having resilient opposing wall portions providing therebetween a recess extending through said shank into said teeth, a relatively thin blade separate from said member disposed within said recess, and means for maintaining said blade in position therein with said resilient wall portions in clamping relation thereto; said blade being substantially coextensive in length with said teeth and having a cutting edge disposed at an angle to a line passing through the ends of said teeth.

Signed at the city of New York, in the county of New York and State of New York, this 11th day of October, one thousand nine hundred and twenty-four.

JOHN D. CARUSO.
